UNITED STATES PATENT OFFICE

2,052,404

FLUID DISPENSING APPARATUS

William K. Kearsley, Schenectady, N. Y., assignor to General Electric Company, a corporation of New York

Application September 28, 1934, Serial No. 745,879

5 Claims. (Cl. 240—2)

My invention relates to fluid dispensing devices and more particularly to gasoline dispensing pumps for filling the tanks of automobiles.

One object of my invention is to provide an improved light for illuminating the inside of the tank which is being filled.

For a better understanding of my invention, together with other and further objects thereof, reference is had to the following description, 10 taken in connection with the accompanying drawing, and its scope will be pointed out in the appended claims.

The well known gasoline dispensing pumps, which are now used at automobile service stations, are equipped with a flexible hose, at the end of which a nozzle is provided for projecting into the tanks of automobiles. With this equipment it is practically impossible for an attendant to see where the fluid level is in the tank since 20 practically no light reaches the interior of the tanks even in the day time. In accordance with my invention I provide a lamp at the end of the hose which is attached to the pump and separate this lamp from the fluid stream completely 25 so as to avoid any fire hazard. I then provide a light-reflecting surface on the inside of the hose to prevent absorption of the light emitted by this lamp and transmitted down along the fluid stream into the tank.

30 In the accompanying drawing I illustrate a standard gasoline dispensing pump 1 having an indicator 2 and an outlet pipe having a T-member 3 attached to the end thereof. The T-member 3 is vertically arranged having attached 35 to its lower end a flexible textile or rubber hose 4 having a nozzle 5 and a valve 6 attached to the end thereof.

At the other end of the T-member I attach a 40 casing 7 having therein a light 8 and a reflector 9. The casing 7 is provided with an opening coinciding with the end of the T-member, which is closed fluidtight by a lens 10. The hose itself is provided on the inside with a smooth light-reflecting surface preferably of white synthetic 45 rubber so that the light projecting from the lamp and reflector will not be absorbed by the hose but such light as might tend to escape from the fluid stream will be reflected back into the stream and will follow it into the tank.

In operation the lamp 8 is lighted when the pump is started. The light flux projected by the lamp is gathered by the reflector and is projected into the fluid stream. This light follows the fluid stream into the tank and is there reflected by the walls of the tank so that the level of the liquid in the tank becomes clearly visible.

What I claim as new and desire to secure by Letters Patent of the United States, is,—

1. In a gasoline dispensing apparatus, the combination of a flexible service hose provided with a nozzle and valve, a feed connection to said hose, and a lamp mounted at said feed connection separated from said fluid stream and arranged to project light into said stream parallel to the axis 15 of said hose.

2. In a gasoline dispensing apparatus, the combination of a flexible hose, a nozzle at one end thereof, a rigid connection at the other end having an inlet passage at an angle to said hose 20 connection and a transparent portion at right angles to the fluid stream in said hose, and a light in back of said transparent portion arranged to direct light through said transparent portion into said fluid stream. 25

3. In a liquid dispensing apparatus, the combination of a flexible hose, a nozzle at one end thereof, a rigid connection at the other end of said hose provided with an inlet passage arranged at an angle to the said hose, a lamp casing 30 mounted on said connection and separated from the hose by a transparent wall, and a lamp mounted in said casing and arranged to project light into said hose.

4. In a liquid dispensing apparatus, the combination of a flexible hose, a rigid connection for said hose provided with an inlet passage at an angle to the axis of said hose, a transparent wall at right angles to the axis of said hose, means for projecting light into said hose through 40 said transparent wall, and a reflecting lining within said hose for preventing the absorption of the said light.

5. In a gasoline dispensing apparatus, the combination of a flexible hose, a nozzle at one end thereof, and a light at the other end of said hose arranged to project light into said hose and through the gasoline therein. 45

WILLIAM K. KEARSLEY.
